UNITED STATES PATENT OFFICE

2,030,068

INCLINOMETER

Floyd Leonard Martin, Laona, Wis.

Application July 18, 1933, Serial No. 681,019

3 Claims. (Cl. 33—220)

This invention aims to provide a simple, automatically-acting means for indicating to the driver of a motor-propelled vehicle, when he is going up hill or down hill, and to indicate the amount of the declivity or rise, the device being so constructed, also, that it will admonish the driver of the vehicle as to what he should do respecting applying the brakes, shifting the gears, and the like.

It is within the province of the disclosure to improve generally and to enhance the utility of devices of that type to which the invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawings:

Fig. 1 shows in vertical longitudinal section, a device constructed in accordance with the invention;

Fig. 2 is an end elevation;

Fig. 3 is an elevation of the dial;

Fig. 4 is a longitudinal horizontal section;

Fig. 5 is a transverse section taken through the equalizer;

Fig. 6 is a transverse section taken through one of the gears.

In carrying out the invention, there is provided a support or casing 1, having a hinged lid 2. Guides 3 are mounted on the sides of the casing 1. Two-part standards 4 are mounted for vertical adjustment in the guides 3. Cushions 5 are interposed between the parts of the standards 4, to take up shocks and jars. Adjusting devices, such as screws 6, are threaded into foot pieces 7 on the bottom of the casing 1, and engage the lower ends of the standards 4.

Compression springs 8 are interposed between the upper ends of the standards 4 and brackets 9 which are secured to the sides of the casing 1. On their upper ends, the standards 4 are supplied with detachable bearings 10. A first shaft 11 is journaled for rocking movement in the bearings 10. The first shaft 11 extends crosswise of the vehicle whereon the device is mounted. The numeral 12 marks a bevelled gear. The bevelled gear 12 has a hub 14. The hub 14 of the bevelled gear 12 is secured to the first shaft 11 by means of a set screw 15, or the like, for adjustment,

Pendulum weights 16 are arranged on each side of the bevelled gear 12. The upper ends of the pendulum weights 16 are connected, adjustably, by means of set screws 17, to the hub 14 of the bevelled gear 12.

A bevelled pinion 18 meshes with the bevelled gear 12. The bevelled pinion 18 is secured at 18 to a second shaft 19, which extends longitudinally of the vehicle. The second shaft 19 is journaled in detachable bearings 20 carried by pedestals 21 and 22, mounted at their lower ends on the bottom of the casing 1. The pedestal 21 preferably is somewhat higher than the pedestal 22.

An equalizer 23, in the form of a circular receptacle, is adjustably secured at 123 to the second shaft 19, between the pedestals 21 and 22. At its top, the equalizer 23 has a removable filling plug 24. In the lower part of the equalizer 23 there is an upwardly-extended radial partition 25. The partition 25 has openings 26. A quantity of liquid 27, which may be mercury or any other liquid, is mounted in the lower part of the equalizer or receptacle 23 on opposite sides of the partition 25.

On the forward end of the second shaft 19 there is a hub disk 28. A translucent dial 29 abuts against the hub disk 28 and is held to the end of the second shaft 19 by a securing element, such as a screw 30. The instrument board is marked by the numeral 41. The support or casing 1 abuts against the forward side of the instrument board 41. A cover plate 141, which may be made of glass or other suitable material, abuts against the rear side of the instrument board 41. The cover plate 141 is contained within a shield 34. Securing elements 35 connect the margin of the shield 34, and one end of the support or casing 1, with the instrument board 41, and, thus, the parts are held together securely but detachably, upon the instrument board.

The shield 34 has an upper arcuate opening 36. Adjacent to the opening 36, an index 39 is marked on the shield 34. There is a second arcuate opening 37 in the shield 34. A third arcuate opening 38 is formed in the shield 34, below the opening 37. The opening 36 is above the center of rotation of the shaft 19, and the openings 37 and 38 are below the center of rotation of said shaft.

The dial 29 is marked with an empirical scale 40, reading in opposite directions from a zero point at the top of the dial. Within the circle described by the scale 40, the dial 29 is marked with the word "Slow", shown at 41, with the 55

word "Brakes" shown at 42, with the word "High" shown at 43, with an abbreviation of the word "Intermediate", shown at 44, and with the word "Low", shown at 45. The markings at 41, 42, 43, 5 44 and 45 are arranged in a circle. Within this circle, the face of the dial 29 is supplied with a red sector 46. The red sector 46 is disposed adjacent to the word "Slow" shown at 41, and the word "Brakes" shown at 42. The face of the 10 dial 29 has a blue sector 47, disposed adjacent to the word "Low" shown at 45, and to the intermediate abbreviation 44. Between the sectors 46 and 47 is a small white sector 48, disposed adjacent to the word "High" shown at 43. Al- 15 though the colors red, blue and white have been mentioned, it is to be understood that any desired colors may be used.

In order to illuminate the dial 29, an electric lamp 49 is mounted on the upper end of the pedestal 21. For the further illumination of the dial, and to avoid shadows, another electric lamp 50 may be mounted on the lower part of the said pedestal. In general, however, the dial 29 may be illuminated in any desired way.

25 In practical operation, when the vehicle is ascending a hill or descending a grade, the pendulum weights 16 impart rotation to the shaft 11 and to the gear wheel 12. The gear wheel 12, meshing with the pinion 18, rotates the shaft 19, 30 and the shaft 19 rotates the dial 29. As the dial 29 is rotated, the scale 40 on the dial, cooperating with the index 39, shows the driver of the vehicle that he is on a grade, either up hill or down hill, and indicates also, the gradient. So long as the 35 vehicle is running on the level, the white sector 48 of the dial 29 shows through the opening 37 in the shield 34, the "High" marking 43 shows through the opening 38, and the driver, thus, is admonished that there is no occasion here to shift 40 gears or to apply the brakes. When, however, the vehicle starts to go down hill, the red sector 46 on the dial 29 appears through the opening 37, and the driver is advised that there is good 45 ground for exercising caution in the manipulation of his vehicle. As the vehicle goes down hill, the markings shown at 41 and 42 appear at the opening 38, and the driver thus is informed that he must go slowly, and apply the brakes.

50 When the vehicle goes up hill, the blue sector 47 on the dial 29 appears at the opening 37, in place of the white sector 43, and the driver knows that his vehicle is on an incline. At the same time, the intermediate gear marking 44, or the low gear marking 45, replaces the high gear marking 43 at the opening 38, and the driver knows what action he should take, respecting the shifting of his gears.

The part 23 is called an equalizer, because it tends to cause the device to work evenly. When 60 rotation is imparted to the shaft 19, the liquid 27 in the equalizer 23 is carried to the left or to the right in Fig. 5 of the drawings, thereby to offset the movement of the bevelled gear 12, but the liquid gradually leaks through the openings 26 65 in the partition 25 of the equalizer 23 and assumes a level. The equalizer 23, and its contents

27, therefore, do not act as a continuing offsetting weight.

The zero mark on the dial 29 may be brought into coincidence with the index 39 on the shield 34 by loosening the screw 30, and turning the dial 5 29 circumferentially. By manipulating the screws 6 of Fig. 6, the standards 4 may be adjusted vertically in the bearings or guides 3, and, thus, an accurate and proper mesh between the gear members 12 and 18 may be brought about, 10 to the end that these members may operate smoothly and without binding.

Having thus described the invention, what is claimed is:

1. An inclinometer comprising a box-like support including sides and a bottom, guides mounted on the sides of the support, brackets mounted on the sides of the support, above the guides, standards mounted for vertical sliding adjustment in the guides, compression springs interposed between the brackets and the upper ends of the standards, adjusting devices movable in the bottom and engaging the lower ends of the standards to raise and lower them, a first shaft carried for rotation on the standards, a second 25 shaft disposed at right angles to the first shaft and carried for rotation on the support, means for operatively connecting the shafts, gravity-actuating means for operating the first shaft, and indicating means carried by the second shaft. 30

2. An inclinometer comprising a box-like support including sides and a bottom, guides mounted on the sides of the support, brackets mounted on the sides of the supports, two-part standards mounted for vertical sliding adjustment in the 35 guides, cushions interposed between the inner ends of the parts of the standards, compression springs interposed between the brackets at the upper ends of the standards, adjusting devices movable in the support and engaging the lower 40 parts of the standards, to raise and lower the standards, a first shaft carried for rotation on the standards, a second shaft disposed at right angles to the first shaft and carried for rotation on the support, intermeshing bevelled gears 45 connecting the shafts, gravity-actuating means for operating the first shaft, and indicating means carried by the second shaft.

3. An inclinometer comprising a support including sides and a bottom, guides mounted on the sides, standards vertically adjustable in the guides, brackets mounted on the sides above the standards, compression springs interposed between the brackets and the standards, means carried by the bottom for raising and lowering the standards, a first shaft mounted to rotate on the standards, a second shaft arranged at right angles to the first shaft, means for connecting the shafts operatively, spaced pedestals mounted 60 on the bottom, and wherein the second shaft is journaled, an equalizer secured to the second shaft and located between the standards, and indicating means on the second shaft, to the rear of the rear pedestal. 65

FLOYD LEONARD MARTIN.
